4 Claims. (Cl. 88—24)

1

My invention relates to apparatus for clamping a copy board fast on the base plate of a photographic enlarging apparatus. Clamping mechanisms for clamping a copy board to a base plate of an enlarging apparatus have been known in which the parts have been clamped by a tensioning member carried on the base plate as well as on the copy board which, by the actuation of a catch or handle, in some cases accompanied by spring action, clamped the parts together. In the prior apparatus the tensioning means itself was placed in the base plate while the copy board carried a guiding groove to receive a sliding member serving as the tightening member. The actuating grip for the clamping was in any case in the base plate. This type of apparatus required two catches for the mounting of the copy board on the base plate. Moreover, the tensioning member standing up from the plane of the base plate was a hindrance to the application of other copy boards not provided with a guiding groove to receive the tension member.

My invention obviates these disadvantages in the kinematic transformations of the tension device by mounting the tensioning member freely movable along a guiding rail arranged parallel to, and within, the copy board and subject to the action of springs. The gripping member grips by means of a guiding head in an undercut guiding groove set into the base plate.

In a preferred embodiment of the invention the rail carrying the gripping member is hung on links within the hollow copy board and is drawn inwardly by springs. At the same time the guide rail can be clipped to the side wall of the hollow copy board by means of a projection, band, collar, etc.; it projects through a corresponding opening in the side wall of the copy board to contact with an eccentric lever mounted on the side wall of the copy board. The gripping member itself is preferably supported on the rail by means of idler rolls and carries a stem with a cylindrical band of greater diameter with which it grips the undercut guide groove set in the base plate. The range of swinging of the rail hangers and the height of the hollow copy board are sufficient to permit the gripping member to be drawn by the springs completely into the copy board.

Through the above invention all actuating elements of the gripping device are brought within the copy board and can be actuated by a single handle which at the same time serves as a handle for positioning the copy board on the base plate.

The various features of the invention are illustrated by way of example in the accompanying drawings, in which:

2

Fig. 1 is a vertical section of a copy board and ground or base plate of a photographic enlarging apparatus provided with the gripping device of my invention, and

5 Fig. 2 is a bottom plan of the copy board of Fig. 1.

Referring to the accompanying drawings, a base plate of a photographic enlarging apparatus is provided in the usual manner with a supporting post 2. It also has an inset, undercut, guide groove 3. On the base plate a copy board 4 is slidably arranged. It comprises a box-like hollow body, open on one side, with the open side placed on the base plate 1. On its upper side it carries a replaceable border mask 5. Within the copy board 4 a guide rail 7 is hung on links 6. Springs 8 acting on the parallelogram 6, 7, 6 thus formed strive to draw the guide rail 7 into the interior of the copy board. A peg 9 extending from the guide rail 7 projects through an opening 10 in the side wall 11 of the copy board. An eccentric lever 12 mounted on the side wall of the copy board 4 extends into the path of movement of the peg 9 so that by swinging the eccentric lever the rail 7 can be shifted lengthwise. The actuating lift of the lever 12 on one side and an enlargement 13 of the rail on the other side limit the movement of the guide rail 7.

The guide rail 7 carries a grip member 15 freely movable lengthwise of the rail on rolls 14. The grip member 15 carries a cylindrical peg 16 with a cylindrical ring 17 of greater diameter extending into the undercut guide groove of the base plate 1. The arrangement of the guide groove in the base plate 1 and the guide rail 7 in the copy board 4 is so selected that their lengths in normal positions of use are at right angles. However it is possible to turn the copy board 4 about the grip member 15. The copy board 4 can be slid 40 to any desired position on the base plate and gripped to the base plate.

The manner of using the apparatus is as follows:

In mounting the copy board on the base plate 45 1, the grip member 15 is depressed by means of the eccentric lever 12, placed into an enlargement 18 of the recessed guide groove 3 and moved into the guide groove 3, thereby uniting the copy board to the base plate. Upon releasing the eccentric lever 12 the springs 8 draw the guide rail 50 into the interior of the copy board and, through the grip member 15, grips the copy board 4 to the base plate. The grip may be released at any time by depressing the eccentric lever 12.

55 The invention contemplates that the apparatus can also be made without the addition of the ec-

centric lever 12. In this case the tension springs 8 continuously clamp the copy board 4 to the base plate by means of the grip member 15, so that a sliding of one relative to the other is possible by overcoming the gripping force. This gripping force will be so adjusted that the shifting of the copy board relative to the base plate 1 may be obtained by gentle pressure but a shifting of the copy board is not caused by use of the paper holder or border mask 5.

Having described my invention, what I claim is:

1. A copy board mounting for photographic enlarging apparatus which comprises a base plate having an undercut groove in its upper surface, a hollow copy board on said base plate, a guide rail within said copy board, said copy board being open below said guide rail, a grip member mounted on and slidable along said guide rail and having a gripping head extending into said undercut groove to engage said groove when drawn upwardly, and tensioning means comprising swinging links to support said rail and a spring to swing said links to upward position to draw said guide rail and grip member upwardly.

2. A copy board mounting for photographic enlarging apparatus which comprises a base plate having an undercut groove in its upper surface, a hollow copy board on said base plate, a guide rail within said copy board extending through an opening in the side wall of said copy board and provided with a stop engaging the inner surface of said side wall, said copy board being open below said guide rail, a grip member mounted on and slidable along said guide rail

5 and having a gripping head extending into said undercut groove to engage said groove when drawn upwardly and tensioning means comprising swinging links to support said rail and a spring to swing said links to upward position to draw said guide rail and grip member upwardly.

10 3. A copy board mounting for photographic enlarging apparatus which comprises a base plate having an undercut groove in its upper surface, a hollow copy board on said base plate, a guide rail within said copy board, said copy board being open below said guide rail, a grip member provided with guide and supporting rolls running on said rail and slidable along said guide rail and having a gripping head comprising a cylindrical stem extending into said groove and a cylindrical enlargement extending into the undercut part of said groove to engage said groove when withdrawn upwardly and tensioning means to draw 15 said guide rail and grip member upwardly.

20 4. The copy board of claim 1 in which the guide rail movement and the dimension of the gripping head are such that the head may be drawn completely within the copy board.
